(57) **CLAIM**

The ornamental design for a cage for ceiling fan and light, as shown and described.

DESCRIPTION

FIG. 1 is a top, front side perspective view of a cage for ceiling fan and light, showing my new design;
FIG. 2 is a front elevational view thereof;
FIG. 3 is a top plan view thereof; and,
FIG. 4 is a bottom plan view thereof.
The back, right, left side views are omitted as they are identical with the front view.
The broken lines shown in the drawings illustrate portions of the cage for ceiling fan and light that form no part of the claimed design.
